UNITED STATES PATENT OFFICE.

CHARLES ELWOOD ARNOLD, OF WILMINGTON, DELAWARE, ASSIGNOR TO E. I. DU PONT DE NEMOURS POWDER COMPANY, OF WILMINGTON, DELAWARE, A CORPORATION OF NEW JERSEY.

MACHINE FOR COATING.

1,177,006.

Specification of Letters Patent. Patented Mar. 28, 1916.

Application filed December 17, 1914. Serial No. 877,642.

To all whom it may concern:

Be it known that I, CHARLES ELWOOD ARNOLD, of Wilmington, in the county of New Castle, and in the State of Delaware, have invented a certain new and useful Improvement in Machines for Coating, and do hereby declare that the following is a full, clear, and exact description thereof.

My invention relates particularly to an improvement in apparatus for producing coated fabrics but, more especially, woven fabrics carrying a coating or layer of a nitrocellulose composition.

The object of my invention is to provide an apparatus capable of producing a product of this kind in which the layer of composition carried by the fabric will be very effectively and securely anchored on the fabric, and in which the coating composition will adhere in an effective manner to the fabric.

More especially the object of my invention is to produce goods of the quality stated without the use of a special cementing coat and to provide the total thickness of the coating in one operation.

While my invention is capable of embodiment in many different forms, for the purpose of illustration I have shown only one form thereof in the accompanying drawings, in which the figure is a diagrammatic side elevation of an apparatus made in accordance with my invention.

Referring to drawing I have provided a shaft 1 carrying a shell 1^a on which the roll of goods is carried. The shaft is provided with any suitable device to insure that the goods being pulled off the roll will be taut. The goods pass from the shell 1^a over two supporting rolls 2 and 5. Between these supporting rolls there is a doctor or smear-on blade 4 in front of which is carried a body or plastic or paste 3. The goods thus treated pass into an evaporating chamber 6 in which the major portion of the solvent is evaporated and recovered. It is undesirable to evaporate the entire amount of solvent as the coated goods when leaving the same pass to calendering rolls 7, where it must be in a pliable condition. The object of the calendering rolls 7 is to give the coated fabric a uniform thickness and render the coating smooth. They need not be very large or heavy rolls as the plastic after coming from the drying chamber is prop-

erly coated and anchored to the fabric but on account of the method of applying the coating in the form of a paste the goods are somewhat too rough to emboss, and the rolls 7 are used simply to smooth the plastic 60 and give the desired uniformity of thickness. The rolls 7 may also be engraved so as to give an embossed pattern on the goods, thereby serving the double purpose of gag- 65 ing and embossing the goods. I have also provided a winder 8 which may be so constructed as to wind up the finished product and keep the tension on the goods through the entire train of the apparatus.

In preparing coated fabrics by the well-known coating machine, which consists of a doctor blade and a drying device, it is customary to obtain the desired thickness of coating by applying a number of successive layers or coatings and evaporating the solvent after each application. If a coating of the total thickness desired is applied at one time in order to reduce the number of operations, the product is not satisfactory because of pin-holes that are formed when the solvent is evaporated. I avoid this difficulty by using a thicker, that is, pasty coating material and preferably pass the coated material between calender rolls before all the solvent has been evaporated. The composition may be any suitable nitrocellulose 75 composition containing volatile solvents. It may also contain any suitable oil or pigment. This calendering operation reduces the coating to a uniform thickness and eliminates 80 the pin-holes. Furthermore, by the use of my invention, the coating is firmly anchored to the fabric because the coating material when applied contains sufficient solvent to enable it to penetrate the interstices of the 85 fabric.

While I have described my invention in detail, I wish it to be understood that many changes may be made therein, without departing from the spirit of my invention. 90

I claim:

1. In combination, means for applying a pyroxylin coating to a fabric, a partial drier and pressure rolls for the coated fabric immediately beyond the drier. 105
2. In combination, means for applying a pyroxylin coating to a fabric, a partial drier and embossing pressure rolls for the coated fabric immediately beyond the drier. 110
3. In combination, means for applying 110

a pyroxylin coating to a fabric, comprising a doctor and fabric-supporting rolls at either side thereof, a partial drier and pressure rolls for the coated fabric immediately beyond the drier.

4. In combination, means for applying a pyroxylin coating to a fabric, comprising a doctor and fabric-supporting rolls at either side thereof, a partial drier and em-

bossing pressure rolls for the coated fabric 10 immediately beyond the drier.

In testimony that I claim the foregoing I have hereunto set my hand.

CHARLES ELWOOD ARNOLD.
